UNITED STATES PATENT OFFICE.

GORDON G. SAPP, OF CHICAGO, ILLINOIS.

DESIGN FOR A COFFEE-POT.

50,141.

Specification for Design.

Patented Jan. 2, 1917.

Application filed September 13, 1915. Serial No. 50,518. Term of patent 7 years.

To all whom it may concern:

Be it known that I, GORDON G. SAPP, a citizen of the United States, residing at Chicago, in the county of Cook and State of Illinois, have invented a new, original, and ornamental Design for Coffee-Pots, of which the following is a specification, reference being had to the accompanying drawing, forming part thereof.

The figure is a side elevation of a coffee pot showing my new design.

I claim:

The ornamental design for a coffee pot, as shown.

GORDON G. SAPP.

Witnesses:

MILDRED STUMPF,
KATHARINE GERLACH.
